UNITED STATES PATENT OFFICE.

ISAAC F. ROOT AND WILLIAM O. SILVEY, OF MIDDLEPORT, OHIO.

FUNNEL.

SPECIFICATION forming part of Letters Patent No. 531,388, dated December 25, 1894.

Application filed September 19, 1894. Serial No. 523,497. (No model.)

To all whom it may concern:

Be it known that we, ISAAC F. ROOT and WILLIAM O. SILVEY, citizens of the United States, residing at Middleport, in the county 5 of Meigs and State of Ohio, have invented a new and useful Funnel, of which the following is a specification.

This invention relates to an improvement in that class of funnels wherein means are provided for adjusting the funnel to the various heights of receptacles which are to be filled thereby; and it consists in certain improved features of construction and combination and arrangement of parts, having for a principal 15 element a counterbalancing weight, the function of which is to hold the funnel at various positions, as will be understood.

In the drawings: Figure 1 represents a perspective view of my complete device; Fig. 2, 20 a vertical section thereof; Fig. 3, a detail section on the line $x-x$ of Fig. 2.

The reference numeral 1 indicates the main standard of our device, which may be formed of cast or wrought metal, or, if so desired, of 25 tin tubing. The standard is formed with an enlarged base 2, by which the arrangement may be secured to the counter of the store, as shown in Fig. 1, said base being extended about one-fourth the length of the standard. 30 The standard 1 is formed hollow and has its upper end provided with two vertical and oppositely-arranged slots 3, in which the plates 4 are rigidly secured.

Revolutely journaled in the respective ends 35 of the plates 4, are the pulleys 5, over which the cords 5^a pass. The cords 5^a may be of an integral piece or may be separate, as desired, and are passed from the pulleys 5 downwardly to the loop 6 of the weight 7, to which 40 weight they are connected through the medium of the loop. The remaining ends of the cords 5^a proceed out of the slots 3 and down the opposite sides of the standard 1, through the grooves 8 of said standard, and to the 45 eyes 9 of the sleeve 10. Here the cords are securely fastened.

The weight 7 is arranged in the standard 1 so as to be capable of vertical movement therein, and by this means the sleeve 10 is balanced on the standard, the said sleeve 50 being capable of moving vertically on the standard, while it is prevented from turning

thereon by means of the eyes 9, which fit within the grooves 8, so as to be capable of moving longitudinally therein.

Rigidly secured to the sleeve 10, by soldering or otherwise, are the funnels 15, which are preferably three in number, and which are formed with the raised partitions 16, whereby to prevent the contents from being spilled. 60 The lower ends of the funnels are formed with the nozzles 17, which permit the escape of the matter that may be contained by them.

In the use of our invention, the standard 1 should be secured to the counter of the store, 65 as shown in Fig. 1. Supposing, now, that it is desired to introduce flour or any similar substance into a bag or bucket; the funnels should be adjusted to the height thereof and filled with the said substance, whereupon it 70 will flow out and into the receptacle, as will be understood. After the receptacle has been filled, the funnels may be raised out of engagement therewith, and so they may remain until again used. It will be observed that 75 the grooves 8 of the standard completely receive the cords 5^a and give the arrangement a neat and uniform appearance. They are principally provided, however, to receive the eyes 9 of the funnel sleeve 10, so as to allow 80 the said sleeve easy longitudinal movement, and so as to restrict the sleeve in rotary movement.

Various changes in the form, proportion, and the minor details of construction may be 85 resorted to without departing from the principle or sacrificing any of the advantages of this invention.

Having described our invention, we claim—

1. The combination of a vertical standard, 90 a funnel movable vertically thereon, a weight counterbalancing the funnel and movable vertically also, a cord connecting the weight and funnel, and an idler pulley over which the cord passes, substantially as described.

2. The combination of a vertical standard hollow throughout its interior, a funnel movable vertically on the standard, a weight movable in the interior of the standard, an idler pulley at the upper end of the standard, and 100 a cord connected to the weight and to the funnel and passing over the idler pulley, substantially as described.

3. The combination of a standard hollow

throughout its interior and having an exterior and longitudinal groove, a funnel movable vertically on the standard and provided with an inwardly-projecting eye extending into the 5 groove, a weight arranged and movable in the standard, a cord connected to the eye of the funnel and to the weight and passing through the groove of the standard, and an idler pulley over which the cord passes, substantially 10 as described.

4. The combination of a vertical standard hollow throughout its length and provided with two exterior and longitudinal grooves, a funnel movable vertically on the standard and 15 provided with two eyes fitting respectively

within the grooves of the standard, a weight movable in the standard, two cords connected to the weight and to the respective eyes of the sleeve, and passed through the respective grooves of the standard, and two idler pulleys 20 over which the cords are passed, substantially as described.

In testimony that we claim the foregoing as our own we have hereto affixed our signatures in the presence of two witnesses.

ISAAC F. ROOT.
WILLIAM O. SILVEY.
